(57) CLAIM

The ornamental design for a firearm thumb support, as shown and described.

DESCRIPTION

FIG. 1 is a perspective view of a firearm thumb support. FIG. 2 is another perspective view thereof. FIG. 3 is a side view thereof. FIG. 4 is a front view thereof; and, FIG. 5 is a side view of the firearm thumb support in use configuration with an unclaimed firearm. The broken lines in FIG. 5 depict an unclaimed rifle included for environmental context and form no part of the claimed design.
